SPECTRAL FLAME BURNERS AND BURNER APPARATUS

Jack Isreeli, Tuckahoe, N.Y., assignor to Technicon Instruments Corporation, Chauncey, N.Y., a corporation of New York

Filed Oct. 7, 1960, Ser. No. 61,222

5 Claims. (Cl. 88—14)

This invention relates to spectral flame burners and burner apparatus for providing a spectral flame for the quantitative analysis of various liquids in respect to one or more substances therein.

One object of the present invention is to provide a spectral flame burner which operates with an auxiliary flame and which is so constructed that transfer of heat from the auxiliary flame to the burner body is greatly minimized.

Another object is to provide a spectral flame burner which is well adapted to provide a high temperature flame without requiring water cooling of the burner body.

Another object is the provision of spectral flame burner apparatus which includes improved auxiliary devices for premixing the fuel gas and combustion-supporting gas to form a combustible gaseous mixture for both the auxiliary flame and the spectral flame.

Another object is to provide a spectral flame burner with sample feed means which minimize the effect of pressure variations of the sample due to the treatment thereof for spectral flame analysis.

A further object is generally to provide a spectral flame burner of improved design which is simple in construction and inexpensive to manufacture.

The above and other objects, features and advantages of the invention will be fully understood from the following description considered in connection with the accompanying illustrative drawings.

In the drawings:

FIG. 1A is a vertical sectional view of the spectral flame burner, taken on the line 1A—1A of FIG. 8;

FIG. 1B is a vertical sectional view of the valve block for the spectral flame burner;

FIG. 2 is a top plan view of the burner apparatus, partly in section taken on the line 2—2 of FIG. 1;

FIG. 3 is a front elevational view of the apparatus looking in the direction of arrow 3 of FIG. 1;

FIG. 4 is a side elevational view of part of the apparatus, looking in the direction of arrow 4 of FIG. 2;

FIG. 5 is a vertical sectional view taken on the line 5—5 of FIG. 1;

FIG. 6 is a horizontal sectional view, on a larger scale, taken on the line 6—6 of FIG. 1;

FIG. 7 is a horizontal sectional view, on a larger scale, taken on the line 7—7 of FIG. 1; and

FIG. 8 is a horizontal view, on a larger scale, taken on the line 8—8 of FIG. 1.

Referring now to the drawings in detail, the spectral flame burner apparatus 10 of the present invention comprises a spectral flame burner 12 and a valve block 14 which is spaced from the burner by the rigid tubes 16 and 18 on which the burner 12 is supported and which transmit a combustible gaseous mixture from the valve block to the burner. The valve block is secured to a valve cover plate 20 by bolts 21 and a gasket 22 is interposed between the valve block and the cover plate. The valve cover plate is provided with bolts 24 for securing the apparatus to a support member which is not shown.

Burner 12 comprises a main body part 26 which has a central vertical bore 28 which provides a vertical passage for the combustible gaseous mixture consisting of a suitable gaseous fuel for example propane, cyanogen, etc., and a gas for supporting combustion, for example

2

oxygen. The bore extends to the upper end or tip of the body part to provide a central opening 30 at said tip. A capillary tube 32 of small diameter extends through the bore and the upper outlet end of the tube is at opening 30 for introducing the liquid to be analyzed into the main flame of the burner whose base is formed at opening 30 to form the spectral flame. The diameter of tube 32 is slightly less than the diameter of opening 30 so that the combustible gaseous mixture may flow out of the burner body into the spectral flame. Tube 32 is mounted in a capillary sleeve 34 which is centrally positioned in bore 28 by the screws 36 to provide clearance between the walls of the bore and the outer surface of the capillary sleeve for passage of the gaseous mixture. The tubes 32 and 34 are connected to a plug 38 which is screwed into the lower end of the body part 26 to secure the tubes in position in the bore 28.

A series of vertical tubes 40 is provided at the upper portion of the body part 26 of the burner and are arranged in a circle adjacent opening 30 and are spaced from each other and from the arcuate walls 42 of the upper portion of the body part. The tubes transmit a combustible gaseous mixture for ignition at the upper ends of the tubes to provide an auxiliary flame which surrounds the spectral flame and is close to it to prevent the spectral flame from being extinguished. Because of the spacing between the tubes 40 and the walls 42 of the body part of the burner, a heat insulating air space is provided between the tubes and the upper portion of the body part to minimize heat transfer from the hot tubes to the body part and thereby help prevent vaporization of sample flowing in tube 32. Such vaporization is to be avoided so that a constant flow of sample is transmitted to the spectral flame. The tubes are secured at their lower ends to the body part of the burner but since the tubes are relatively small, little heat is transmitted by conduction from the lower parts of the tubes to the burner body. It will be apparent that an effective spectral flame burner is thus provided which is well adapted to provide a flame of high temperature especially useful in spectral flame analysis, without requiring water cooling of the burner. In this regard it will be understood that the speed of the combustible gaseous mixture to the opening 30 is relatively high so that the spectral flame is spaced slightly above the upper end of the body part of the burner out of contact therewith and hence does not transmit any appreciable amount of heat to the burner. On the other hand, the speed of flow of the combustible gaseous mixture for the auxiliary flame is considerably less than the speed of flow of the gaseous mixture for the spectral flame so that the auxiliary flame burns at the upper end of tubes 40 and heats said tubes by conduction. Although three tubes 40 are shown, it is within the scope of the invention to provide more than three tubes, if desired.

Tube 16 transmits the combustible gaseous mixture from the valve block 14 to the burner 12 and the outlet end 44 of the tube is mounted in the lower portion of the body part 26 of the burner and is in communication with a passage 46 which communicates with the bore 28. Tube 18 transmits the combustible gaseous mixture for the auxiliary flame from the valve block 14 to the burner and the outlet end 48 of the tube is mounted in the lower portion of the body part 26 of the burner. A vertical tube 50 connects tube 18 with an annular member 52 mounted on the body of the burner and tube 50 is in fluid flow communication with an internal annular passage 54 provided in member 52. In communication with the lower end of each of the tubes 40 for the auxiliary flame is a vertical passage 56 and a horizontal passage 58 formed in the body of the burner. Passage 58 is in communication with annular passage 54. It will be apparent that tube 50 transmits the combustible gaseous mixture to the annular

passage 54, which acts as a manifold, and the mixture is transmitted from the manifold to each of the tubes 49 through passages 58 and 56, respectively.

The inlet ends 60 and 62 of tubes 16 and 18, respectively, are mounted in a block 64 which is secured to the valve block 14, at the upper part thereof, by bolt 66. The upper part of the valve block contains two horizontal passages 68 and 70 which are in communication with the inlet ends 60 and 62, respectively, of tubes 16 and 18. Disposed in each of these passages 68 and 70 is a mixer 72 which is threaded at one end onto a threaded pin 74 which in turn is threaded into block 64. It will be noted that the outer surfaces of mixer 72 are spaced from the side walls and end wall which define the passage 68 so that the combustible mixture flows into passage 68 and enters the mixer through the aperture 76 at one end of the mixer tube 78. A series of mixing cups 30 having apertures 82 are provided in mixer tube 78 and are effective to thoroughly mix together the fuel gas and oxygen which are transmitted to passages 68 and 70 to provide the combustible gaseous mixture for the main flame and the auxiliary flame, respectively. It will be apparent that the gases which form the combustible mixture are mixed at a position which is remote from the burner, namely in the valve block 14, and the mixture is transmitted to the burner via tubes 16 and 18. The combustible mixture passes into tubes 16 and 18 from the mixers 72 through the passage 83 provided in each pin 74.

The gases for the combustible mixture are supplied to the valve block 14 from tanks (not shown) or other suitable source, and fitting 84 is provided in the valve block for the fuel gas and fitting 86 is provided in the valve block for the combustion supporting gas. Needle valves are provided in the valve block 14 for controlling the amount of gas which is supplied to the mixers 72. The needle valves are identical in construction and the control and flow of the fuel gas for both the spectral flame and the auxiliary flame are the same as the flow and control of the combustion supporting gas for the spectral flame and the auxiliary flame. Fitting 84 for the fuel gas is in communication with a passage 88 in the valve block and fitting 86 for the combustion supporting gas is in communication with a passage 90 in the valve block. A vertical passage 92 in the valve block connects passage 88 with a passage 94 and the size of the opening 96 of passage 94 is controlled by needle valve 98 which is in the fuel control valve for the spectral flame. Similarly, a vertical passage 100 in the valve block connects passage 90 to a passage 102 whose opening is controlled by a needle valve 104 for controlling the amount of combustion supporting gas which is supplied for the spectral flame. A passage 106 connects passage 68 with opening 108 which is in communication with passage 94. A passage 110 connects passage 106 with opening 112 which is in communication with passage 102. In this manner, a stream of combustion supporting gas flowing in passage 110 is introduced into passage 106 where it joins a stream of fuel gas and the mixture is transmitted to passage 68, via a portion of passage 106, and enters the mixer 72 which is provided in passage 68. From the mixer the mixed gases are supplied to the burner for the spectral flame, via tube 16.

The gas mixture for the auxiliary flame is supplied to the burner in a similar manner. A tube 114 connects passage 92 for the fuel gas to a passage 116 whose opening 118 is controlled by a needle valve 120 which controls the amount of fuel gas for the auxiliary flame. It will be understood that tube 114 is of relatively small diameter and transmits small quantities of fuel gas from passage 92 since the auxiliary flame requires substantially less fuel gas than the spectral flame. The provision of small tube 114 permits effective control by valve 120 of the amount of fuel gas supplied for the auxiliary flame and eliminates the necessity for providing very small diameter passages for the fuel gas in the valve block and corre-

sponding very small needle valves for controlling the flow of gas in such small diameter passages. Similarly, a small tube 122 connects passage 100 with passage 124 whose opening is controlled by a needle valve 126 for controlling the amount of combustion supporting gas which is supplied to the auxiliary flame. A passage 128 in the valve block connects passage 70 with an opening 130 which is in communication with passage 124 and a passage 132 in the valve block connects passage 128 with an opening 134 which is in communication with passage 116 so that the stream of fuel gas flowing in passage 132 for the auxiliary flame is introduced into the stream of combustion supporting gas flowing in passage 128 for the auxiliary flame and the mixture of the gases is transmitted the passage 70, via a portion of passage 128, where it is introduced into the mixer 72 in passage 70 and flows from said mixer to the burner, via tube 18.

A cover plate 136 is secured to the valve block by bolt 138 and overlies tubes 114 and 122 to provide a protective covering for the tubes. A sample feed tube 140 is mounted on the side of the valve block 14 and is secured to the valve block by cover 142. The sample feed tube comprises a series of closely wound coils of tubing which provide a circular path of flow for the sample between the inlet end 146 of the sample tube and the outlet end 148 thereof. It will be understood that outlet end 148 is connected to the inlet end 150 of sample tube 32 of the burner by a suitable length of tubing which is not shown. The relatively small internal diameter of the sample tube 140 which is preferably equal to or less than the internal diameter of burner fuel tube 32 and the length of the path of flow of the sample provided by the coils 144 introduces a considerable amount of friction to the flow so that the pressure in the feed tube 140 is sufficiently high to minimize the effect of pressure variations or surges in the sample flow.

It will be understood that while the invention has been described with respect to an air cooled burner pursuant to one or more objects of the invention and the preferred embodiment thereof, it is within the scope of the invention to provide a water cooled burner having one or all of the various features disclosed herein, unless otherwise indicated in the claims. Also while I have shown and described the preferred embodiment of the invention, it will be understood that the invention may be embodied otherwise than as herein specifically illustrated or described, and that certain changes in the form and arrangement of parts and in the specific manner of practicing the invention may be made without departing from the underlying ideas or principles of this invention within the scope of the appended claims.

I claim:

1. A spectral flame burner, comprising a body part provided with a vertical bore and an opening at the upper end of said body part in communication with said bore, said body part having a passage in communication with said bore below said upper end for transmitting a combustible gaseous mixture into the bore for ignition near said opening to provide a main flame at the upper end of said body part, a tube positioned in said bore and extending longitudinally thereof in communication with said opening for transmitting a sample substance to said main flame for spectral flame analysis, and a coil of tubing of small inner diameter connected to the lower end of said last mentioned vertical tube for transmitting said sample substance to the burner, said coil of tubing minimizing surges or variations in rate of flow of the sample to the flame of the burner due to minor variations of pressure at which the sample substance is transmitted to said coil.

2. In spectral flame burner apparatus, a spectral flame burner, comprising a body part provided with a vertical bore and an opening at the upper end of said body part in communication with said bore, said body part having a passage in communication with said bore below said upper end for transmitting a combustible gaseous mixture into

the bore for ignition at said opening to provide a main flame at the upper end of said body part, a plurality of tubes disposed externally of the burner and having outlets spaced from each other and from said upper end of said body part and mounted in positions for transmitting a combustible gaseous mixture for ignition at the outlet ends of said tubes to provide an auxiliary flame adjacent said opening for the combustible mixture for said main flame, a chamber having an inlet for the combustible mixture and a plurality of outlets to which said tubes are connected, respectively, for the supply of the combustible mixture to said tubes from said chamber, and means including a tube connected to the inlet of said chamber for supporting said chamber and for transmitting the combustible mixture thereto.

3. A spectral flame burner, comprising a body part provided with a vertical bore and an opening at the upper end of said body part in communication with said bore, said body part having a passage in communication with said bore below said upper end for transmitting a combustible gaseous mixture into the bore for ignition near said opening to provide a main flame at the upper end of said body part, a tube positioned in said bore and extending longitudinally thereof in communication with said opening for transmitting a sample substance to said main flame for spectral flame analysis, a coil of tubing of small inner diameter connected to the lower end of said last mentioned vertical tube for transmitting said sample substance to the burner, said coil of tubing minimizing surges or variations in rate of flow of the sample to the flame of the burner due to minor variations of pressure at which the sample substance is transmitted to said coil, and means positioned externally of the burner and spaced from said body part to provide an auxiliary flame adjacent said opening of said body part, and means positioned below said opening of said body part of the burner for supporting said auxiliary flame means.

4. A spectral flame burner, comprising a body part provided with a vertical bore and an opening at the upper end of said body part in communication with said bore, said body part having a passage in communication with said bore below said upper end for transmitting a combustible gaseous mixture into the bore for ignition near said opening to provide a main flame at the upper end of said body part, a tube positioned in said bore and extending longitudinally thereof in communication with said opening for transmitting a sample substance to said main flame for spectral flame analysis, a coil of tubing of small inner diameter connected to the lower end of said last mentioned vertical tube for transmitting said sample substance to the burner, said coil of tubing minimizing surges or variations in rate of flow of the sample to the flame of the burner due to minor variations of pressure at which the sample substance is transmitted to said coil, a plurality of tubes disposed externally of the burner and having outlets spaced from each other and from said upper end of said body part and mounted in positions for transmitting a combustible gaseous mixture for ignition at the outlet ends of said tubes to provide an auxiliary flame adjacent said opening for the combustible mixture for said main flame, and valve controlled gas mixer means for supplying a combustible mixture to said chamber and to said passage to the bore of the burner.

combustible gaseous mixture for ignition at the outlet ends of said tubes to provide an auxiliary flame adjacent said opening for the combustible mixture for said main flame, a valve block, valve controlled passages in said block for the flow therethrough of a fuel gas and a gas to support combustion, gas mixing means in said passages to mix said combustion supporting gas with said fuel gas to form said combustible mixtures, and separate conduits connected to said valve block and to said body part and in communication with said bore and said tubes, respectively, for transmitting the combustible gaseous mixture from said mixing means of the valve block simultaneously to said bore for the main flame of said burner and to said tubes for said auxiliary flame.

5. A spectral flame burner, comprising a body part provided with a vertical bore and an opening at the upper end of said body part in communication with said bore, said body part having a passage in communication with said bore below said upper end for transmitting combustible gaseous mixture into the bore for ignition near said opening to provide a main flame at the upper end of said body part, a tube positioned in said bore and extending longitudinally thereof in communication with said opening for transmitting a sample substance to said main flame for spectral flame analysis, a coil of tubing of small inner diameter connected to the lower end of said last mentioned vertical tube for transmitting said sample substance to the burner, said coil of tubing minimizing surges or variations in the rate of flow of the sample to the flame of the burner due to minor variations of pressure at which the sample substance is transmitted to said coil, a plurality of tubes disposed externally of the burner and having outlets spaced from each other and from said upper end of said body part and mounted in positions for transmitting a combustible gaseous mixture for ignition at the outlet ends of said tubes to provide an auxiliary flame adjacent said opening for the combustible mixture for said main flame, and valve controlled gas mixer means for supplying a combustible mixture to said chamber and to said passage to the bore of the burner.
